REFRIGERATING APPARATUS

George F. Weiher, Dayton, Ohio, assignor to General Motors Corporation, Dayton, Ohio, a corporation of Delaware

Application July 3, 1936, Serial No. 88,810

2 Claims. (Cl. 230—139)

This invention relates to the construction of compressors and particularly to fluid compressors employed in refrigerating systems.

An object of the present invention is to provide 5 an improved compressor construction.

Another object of the present invention is to provide an improved fluid compressor construction wherein parts thereof are connected together by a yieldable connecting means to facilitate assembly of the parts and to provide quiet operation of the compressor without impairing its life.

A still further and more specific object of the invention is to provide a fluid compressor with a yieldable bearing device for the shaft thereof to thereby insure alignment of the shaft within the bearing and to reduce or eliminate clearances therebetween which ordinarily create noises during operation of the compressor.

In carrying out the foregoing objects it is a 20 still further and more specific object of the invention to provide a yieldable bearing device for the shaft of a compressor which while being exposed to refrigerant and lubricant within the compressor is not affected thereby.

Further objects and advantages of the present 25 invention will be apparent from the following description, reference being had to the accompanying drawing, wherein a preferred form of the present invention is clearly shown.

In the drawing:

Fig. 1 is a vertical cross-sectional view of a 30 compressor having my invention embodied therein;

Fig. 2 is a fragmentary vertical cross-sectional view similar to Fig. 1 and showing a yieldable bearing deformed in accordance with the invention; and

Fig. 3 is a fragmentary cross-sectional view taken on the line 3—3 of Fig. 1.

A unit embodying the features of my invention 40 is shown in Fig. 1 of the drawing and is generally designated by the reference character 10. This unit comprises a combined motor and compressor that may be connected with any system utilizing fluid under pressure and in the present instance the compressor is preferably of the type adapted to form a part of a closed refrigerating system (not shown). The unit 10 includes a dome or bell 11 having its bottom edge secured to a base 45 plate 12 to form a sealed enclosure in which is located a cylinder 13 and a piston member 14 providing a compression chamber 15. In the design of compressor disclosed the piston 14 is given a gyroscopic motion by an eccentric 17, formed on the lower end of a drive shaft 18, on which shaft a motor rotor 19 is mounted. The motor rotor 19 is caused to rotate by a motor stator 21. The piston member 14 is adapted to receive a divider block which divides the compression chamber 15 50 so as to cause compression of a fluid therein in

the well-known manner. The fluid or gaseous refrigerant to be compressed by the compressor portion of unit 10 enters the chamber 15 by way of a conduit coupling 22. Compressed fluid is expelled from the chamber 15 into the sealed container, formed by the members 11 and 12, through suitable check valves which may be located in the upper plate 23 and finds its way through suitable passages, such, for example, as the openings 24 and 25, provided in a stationarily mounted 10 shaft 26 disposed within and supporting drive shaft 18, out of the sealed container. Compressed fluid is thereby discharged from unit 10 through the lower end 27 of shaft 26 which end extends outwardly of the sealed container provided by 15 dome 11 and plate 12.

Since compressors of the type herein disclosed impart a gyroscopic motion it is difficult to maintain sufficiently close limits of fit between various parts or elements of the motor-compressor unit 10 during or after the assembly thereof and operation of the unit sets up vibration noises that are objectionable. For example, the fit of dome or bell 11 upon base plate 12 may cause a slight misalignment of the mounting point, designated at 20 28, of shaft 26 relative to the bearing retainer collar or socket 29 secured to the inner surface of the top wall of dome 11. Such a misalignment will cause the stationary shaft 26 to be mounted or disposed at a slight angle to the drive shaft 18 and during operation of unit 10 other parts 25 thereof will also at times be misaligned to cause abnormal clearances between the parts and these clearances will thereby create objectionable noises. Since my invention is particularly directed to eliminating noises during operation of 30 a motor-compressor unit of the type disclosed and wherein the drive shaft is vertically disposed I propose the utilization of a bearing device within the collar or socket 29 which is yieldable 35 and capable of being flexed so as to insure proper alignment of parts of the unit and to eliminate the occurrence of abnormal clearances between 40 the various parts.

I therefore locate or mount a bearing device 45 within the collar or socket 29 which device comprises an outer cylindrical steel or brass tube member 31 having a yieldable collar member 32 therein. The bearing device also includes a bronze collar 33 split as at 34 and disposed within 50 the collar member 32. The collar 33 is split at 34 for the purpose of permitting compression of this collar during insertion thereof into the yieldable collar member 32 and to permit expansion thereof against the walls of the opening in member 32 to 55 thus firmly maintain collar 33 within yieldable member 32. The collar member 32 is made of a yieldable rubber-like material which has the toughness of and resembles vulcanized rubber and which is resistant to the refrigerant and lubricant 60

ordinarily used in refrigerating systems so as to enable same to remain relatively unchanged as to volume and other characteristics in the presence of refrigerants and oils within a refrigerating system. Among the types of materials which may be employed to form the yieldable member 32 I prefer that class of synthetic rubbers known as the polymers of chloro-2-butadiene-1,3. These synthetic rubbers are known to the trade as "Duprene", and are resistant to any action in the presence of the refrigerants commonly used, such as the fluorine derivatives of the hydrocarbons, for example, methyl and ethyl chlorides, or the fluorine derivatives of the hydrocarbons, such as tetrafluoroethane, and these polymers are also resistant to the common lubricants which may be considered to be derivatives of methane, such as mineral oil, which is indicated in Fig. 1 at 36, and employed to lubricate moving parts of unit 10. I have found that a bearing device made of or having a portion thereof made of one of these polymers withstands, in the presence of a lubricant and a refrigerant, without any substantial change in volume and without any substantial change in resiliency and because of the yieldable nature of the material any variations can be taken up by the material of the bearing device. Thus a misalignment of shaft 26 with the bearing mounting or support collar 29 will be taken up by flexing of the member 32 within the bearing device and member 32 will permit the inner bronze collar 33 of the bearing device to align with and fit closely against the portion of shaft 26 adjacent its upper end. It will be noted by referring to Fig. 2 of the drawing and observing the exposed end of the member 32 that this member is twisted or tilted so as to be slightly deformed within the metal portions 31 and 33 of the bearing device, or, in other words, the members 31 and 33 are disposed at a slight angle to one another, to thereby cause the metal member 33 to tightly engage the end portion of shaft 26 throughout the length of the surface thereof adapted to bear against the shaft. This deformation of the member 32 is caused by misalignment of parts of the unit 10 such, for example, as the dome 11 not fitting centrally of the base plate 12 or by shaft 26 not being mounted in the exact center of the unit 10.

It will be seen from the foregoing that the bearing device of the present invention insures a close fit of the shaft therein and permits proper alignment of the shaft bearing surface even though parts or elements of the unit may not be mounted in exact alignment. My improved bearing device is highly important and useful in units of the type disclosed even if the parts of the unit are machined between close limits because the tolerances of the limits of one machined part may not at all times match with the tolerances of limits of other machined parts to be assembled or connected to the one part and thus abnormal clearances occur which create noise during operation of the unit. The split bronze member 33 of my improved bearing device always snugly fits against shaft 26 and in alignment therewith to eliminate any clearance between these parts which may create a noise during operation of the unit. The yielding characteristics of the portion 32 of the bearing device permits alignment of the metal mem-

ber 33 with shaft 26 to thereby insure uniform wear of member 33 and shaft 26. While I have disclosed the improved support as a bearing device in a position to yield and cause proper alignment of certain parts in a specific locality within a unit of the type herein described it is obvious that the improved supporting device may have other uses under similar circumstances in different localities of the same or other units. My improved bearing device or support facilitates the assembly of units of the type described and eliminates the generation of noise thereby without impairing the life of the unit.

While the form of embodiment of the invention as herein disclosed, constitutes a preferred form, it is to be understood that other forms might be adopted, all coming within the scope of the claims which follow.

What is claimed is as follows:

1. A unit forming a sealed chamber containing an operating element, said unit comprising a base plate member having means rigidly secured thereto and extending upwardly therefrom for supporting the operating element, said base plate member also having a peripheral finished surface adapted to be engaged by a closure member, said operating element supporting means and said peripheral finished surface of said base plate member being fixed relative to one another, a dome-shaped closure member having a mounting portion formed on its inner surface integral therewith for receiving the end of said operating element supporting means, said closure member also having a finished surface adapted to conform to and fit over the peripheral finished surface on said base plate member, and said mounting portion of said closure member including a yieldable means to compensate for variations in alignment thereof with said operating element supporting means to permit the finished surfaces of said members to be brought into registration.

2. A unit forming a sealed chamber containing an operating element for circulating a refrigerant comprising a halogen derivative of a hydrocarbon and a lubricant, at least one of which has a deteriorating effect on rubber, therethrough, said unit comprising a base plate member having means rigidly secured thereto and extending upwardly therefrom for supporting the operating element, said base plate member also having a peripheral finished surface adapted to be engaged by a closure member, said operating element supporting means and said peripheral finished surface of said base plate member being fixed relative to one another, a dome-shaped closure member having a mounting portion formed on its inner surface integral therewith for receiving the end of said operating element supporting means, said closure member also having a finished surface adapted to conform to and fit over the peripheral finished surface on said base plate member, said mounting portion of said closure member including a yieldable means to compensate for variations in alignment thereof with said operating element supporting means to permit the finished surfaces of said members to be brought into registration, and said yieldable means of said mounting portion of said closure member being formed of a polymer of chloro-2-butadiene-1,3.
